US00D559814S

(12) **United States Design Patent** (10) **Patent No.:** **US D559,814 S**
(45) **Date of Patent:** **** Jan. 15, 2008**

(54) **MOBILE PHONE**

(75) Inventors: **Bo-Ra Kim**, Seoul (KR); **Sung-Hoon Hong**, Suwon-si (KR); **Beom-Ku Han**, Seoul (KR); **Chang-Hwan Hwang**, Goyang-si (KR)

(73) Assignee: **Samsung Electronics Co., Ltd.**, Suwon-Si (KR)

(**) Term: **14 Years**

(21) Appl. No.: **29/254,282**

(22) Filed: **Feb. 22, 2006**

(30) **Foreign Application Priority Data**

Nov. 14, 2005 (KR) 30-2005-0038225

(51) **LOC (8) Cl.** **14-03**

(52) **U.S. Cl.** **D14/138**

(58) **Field of Classification Search** D14/496, D14/138, 341-347; 455/575.3, 575.1; D21/517, D21/329, 333

See application file for complete search history.
